[57] **CLAIM**

The ornamental design for a spray gun for washing vehicles, substantially as shown and described.

DESCRIPTION

FIG. 1 is an elevational view taken from one side of a spray gun for washing vehicles, the opposite side being a mirror image of the side shown;

FIG. 2 is a top plan view thereof;

FIG. 3 is a bottom plan view thereof;

FIG. 4 is a rear elevational view thereof; and

FIG. 5 is a front elevational view thereof.
